GERALD DEAKIN, OF NEW YORK, N. Y., AND LIPA POLINKOWSKY, DECEASED, LATE OF PARIS, FRANCE, BY EDOUARD FRUM, ADMINISTRATOR, OF PARIS, FRANCE, AS SIGNORS TO INTERNATIONAL STANDARD ELECTRIC CORPORATION, OF NEW YORK, N. Y.

AUTOMATIC AND SEMIAUTOMATIC TELEPHONE EXCHANGE SYSTEM

Application filed May 13, 1930, Serial No. 452,084, and in Great Britain May 14, 1929.

This invention relates to automatic and semi-automatic telephone systems and is concerned more particularly with such systems in which two-wire junctions are provided over which inter-exchange connections are 5 extended.

It is common to provide in such two-wire junctions a transmission bridge from which talking current is fed during conversation in the direction of the calling and called parties. An object of the present invention is the provision of simple and efficient means for cutting out the transmission bridge during the setting up of a connection over the junction and for replacing the bridge immediately the connection has been completed. Such a provision is particularly necessary in a system of the kind to which the invention is 10 described as applied in which revertive controlling impulses are sent over a metallic circuit extending to a register controller.

According to a feature of the invention a relay group associated with a two-wire junction comprises a relay which is adapted to be operated immediately the junction is taken into use and which in its operated condition is adapted to cut out a transmission bridge normally inserted in the junction. The transmission bridge remains cut out during the extension of the connection over one or more switching stages but is reinserted on the completion of the connection in response to the operation of a polarized relay also comprised in said relay group.

According to a further feature in a telephone system in which a registering and controlling mechanism is employed for controlling the extension of a connection over a two-wire junction which normally includes a transmission bridge, means is associated with said junction for cutting out said transmission bridge when the junction is taken into use and for reinserting said bridge on the completion of a connection over the junction, both the operations being brought about responsive to signals transmitted from said registering and controlling mechanism.

The invention is described as applied to a system of the kind described in our co-pending application U. S. Ser. No. 452,083, and

the circuits herein described and illustrated are identical with circuits described and illustrated in that application in which other features are claimed.

In the accompanying drawings Fig. 1 shows a relay group situated at the incoming end of a two-wire junction, whilst Fig. 2 shows a register-controller circuit in which a wanted number is adapted to be recorded and which exercises its controlling action through the medium of revertive impulses sent back from selector switches at the various switching stages as the connection progresses. For a complete understanding of the present invention it has only been thought necessary to include in the present application drawings of the register controller and of the junction relay group, since an understanding of the operation of the system as a whole can be obtained by reference to the main application. Reference characters identical with those in the main application have, however, been used to facilitate a clear understanding of all the circuits shown, so that the circuits not described can be readily followed by reference to the main application.

When a calling party initiates a call to a distant exchange his line is connected over first and second line finders to an idle register controller, Fig. 2 which receives the dialled digits and controls the extension of the connection over a first group finder to a two-wire junction such as IJ Fig. 1. All these operations take place in the manner described in detail in the copending application referred to and it has not been thought necessary to again describe the ordinary operations of the system.

When, as described in the copending application at the end of the first selection the *a* wire is connected to battery in the register circuit over contacts K₇3, Fig. 2, and the *b* wire to earth over contacts K₇4, winding of relay Pr, contacts E₇6, a high resistance supervisory relay S_{br} Fig. 1 which is normally bridged across the junction in series with the low resistance supervisory relay S_{ar} energizes; relay S_{ar} remains unoperated. Relay S_{br} closes a circuit via contacts Br₁ for relay

Ar which locks over contacts Cr1, closes a circuit for relay Br over contacts Ar7, opens the bridge over relay Sbr and completes a metallic through connection over the a and b wires and contacts Ar1—2 and Ar4 to the incoming group finder. Relay Br feeds holding ground forward over the third wire. Relay Cr is now inserted in series in the a wire and is shunted by the resistance R and one of the talking condensers. This relay Cr is polarized and does not operate at this time nor during the further setting up of the connection which takes place in the manner fully described in the copending application under the control of the register circuit.

At the end of a selection or on a premature release when relay Drr, Fig. 2 energizes and brings about the release of the register circuit, a potential of opposite polarity is connected to the a wire for a short interval over contacts Grr5 and Drr4 during the relapse of the slow release relay Grr. Relay Cr which always finds a ground over the start relay (Acr) of the control circuit of a second group of final finder now responds and unlocks relay Ar which cannot re-energize during the slow release period of relay Br. The high resistance bridge relay Sbr now becomes energized to battery and earth at the calling line cord circuit over a relay and a retard and holds relay Br over contacts Br2 and Sbr1. Relay Br holds over its left-hand non-inductive high resistance winding in series with its right-hand winding to economize in current and to render this relay relatively quick to release at the end of conversation. On the reply of the called party talking current is fed over a retard and the supervisory relay Sbr causing the response of the low resistance supervisory relay Sar and a supervisory relay in the calling line cord circuit. Relay Sar holds relay Br. In the case of a premature release of the register circuit is released as described in the co-pending application and the impulse of opposite polarity, previously referred to is sent to the incoming relay group and causes the response of the relay Cr thereat. On the response of relay Cr, however, no circuit is found for relay Sbr and the relay Br releases and initiates the release of the succeeding switches.

A jack OJ is provided for disabling the junction.

What is claimed is:—

55. 1. In or for an automatic or semi-automatic telephone system a relay group associated with a two-wire junction comprising means for cutting out a transmission bridge in said junction during the establishment of a connection over one or more subsequent switching stages and a polarized relay which is adapted to be operated subsequently to bring about the reinsertion of said transmission bridge.
60. 2. A telephone system in which a regis-

tering and controlling mechanism is employed for controlling the extension of a connection over a two-wire junction which normally includes a transmission bridge, in which means is associated with said junction for cutting out said transmission bridge when said junction is taken into use and for reinserting said bridge on the completion of a connection over said junction, both said operations being brought about responsive to signals transmitted from said registering and controlling mechanism.

3. In or for a telephone system a relay group for use at the incoming end of a two-wire junction which normally includes a transmission bridge, said relay group comprising a relay which is adapted to be operated when said junction is taken into use to cut out said transmission bridge and to insert in series with one of the junction conductors a further relay which is adapted to respond subsequently to a signal sent over said junction conductor and to cause thereby the reinsertion of said transmission bridge.

4. A telephone system as claimed in claim 2 in which said means comprises a relay which is normally bridged across the conductors of said junction and operates on the completion of a loop circuit over said conductors when said junction is taken into use said relay being adapted to close a circuit for a further relay which in its operated condition cuts out said transmission bridge and inserts the winding of a polarized relay in series with one of the junction conductors.

5. A telephone system as claimed in claim 2 in which said registering and controlling mechanism exercises its controlling action through the medium of revertive signals sent from switching apparatus at the successive switching stages over a metallic circuit including the conductors of said junction.

6. In a telephone system a two-wire junction, a transmission bridge normally inserted in said junction, means for cutting out said transmission bridge and substituting a metallic circuit over said junction during the establishment of a connection, and means for reinserting said bridge when the connection is completed.

7. In a telephone system, a two-wire junction, a transmission bridge normally inserted in said junction, means for cutting out said transmission bridge during the establishment of a connection over one or more subsequent automatic switching stages and means for automatically reinserting said bridge in case of a premature release by the calling party.

8. In a telephone system, a two-wire junction, a metallic circuit including the two talking conductors of said junction for controlling the operation of an automatic switch at the incoming end thereof, and means for inserting a transmission bridge in said junction on the completion of a connection thereover.

9. In a telephone system, a two-wire junction, a transmission bridge normally inserted in said junction, a relay for cutting out said transmission bridge and substituting a metallic path over said junction, means for operating said relay when said junction is taken into use, a further relay which in its operated condition is adapted to open the circuit of said first relay and means for energizing said further relay at a subsequent stage in the connection.

10. A telephone system comprising a two wire junction having a transmission bridge normally inserted therein, a relay group comprising a relay adapted to be operated immediately said junction is seized to extend a connection, and thereby cut out said bridge, and a polarized relay, whose operation is effective to restore said bridge, having its winding inserted in series with one conductor of said junction during the setting up of the connection, the said polarized relay being adapted to respond to a reversal of current over said junction conductor when the connection is completed or on a premature release by the calling party.

11. In a telephone system comprising a registering and controlling mechanism for controlling the extension of a connection over a two-wire junction which normally includes a transmission bridge, the combination of a relay normally bridged across the conductors of said junction and operative on the completion of a loop circuit over said conductors when said junction is taken into use, a second relay controlled by said relay and adapted when operated to cut out said transmission bridge and to insert the winding of a polarized relay in series with one of said junction conductors, said polarized relay being responsive to a current reversal initiated in said registering and controlling mechanism on the completion of the connection, and means whereby the operation of said polarized relay causes the deenergization of said second relay whereby the transmission bridge is reinserted.

12. A telephone system as claimed in claim 11 in which the operation of said polarized relay also causes said first mentioned relay to be reconnected in bridge across said junction conductors and means is provided whereby on the reply of the called party the winding of said relay is short-circuited to cause a supervisory signal to be sent over said junction.

In witness whereof, we hereunto subscribe our names this 27th day of February, 1930, and 3rd day of February, 1930.

60 GERALD DEAKIN.
EDOUARD FRUM,
